Primary Examiner — Cathron C Brooks*Assistant Examiner* — Andrew T Nemeth(74) *Attorney, Agent, or Firm* — Michael Best and Friedrich LLP(57) **CLAIM**

The ornamental design for a display panel or screen with a graphical user interface, as shown and described.

DESCRIPTION

FIGURE is a front view of a display panel or screen with a graphical user interface showing our new design. The broken lines illustrate portions of the display panel or screen with graphical user interface and portions of an electronic device. The broken lines form no part of the claimed design.
